UNITED STATES PATENT OFFICE.

GEORGE F. CLARK, OF UTICA, NEW YORK.

DESIGN FOR A SPRAYER-BODY.

SPECIFICATION forming part of **Design No. 33,580**, dated November 20, 1900.

Application filed October 27, 1900. Serial No. 34,867. Term of patent 3½ years.

To all whom it may concern:

Be it known that I, GEORGE F. CLARK, a citizen of the United States, residing at Utica, in the county of Oneida and State of New York, have invented and produced a new and original Design for a Sprayer-Body, of which the following is a specification, reference being had to the accompanying drawings, forming a part hereof.

10 Figure 1 shows a perspective view of the sprayer-body of my design. Fig. 2 shows an end view of the same.

The feature of the design is the form and arrangement of the parts constituting the sprayer-body—that is to say, the upper and lower cylindrical portions 1 and 2, substan-

tially of uniform length and size, and the superposed small cylindrical portion 3, arranged substantially as shown.

Having described my invention, what I claim as new, and desire to secure by Letters Patent, is—

The design for a sprayer-body, substantially as herein shown and described.

In witness whereof I have hereunto subscribed my name, in the presence of two witnesses, this 20th day of October, 1900.

GEO. F. CLARK.

Witnesses:

S. A. BROWN,
CHARLES G. IRISH.
